UNITED STATES PATENT OFFICE.

GEORGE W. EDWARDS, OF FORT EDWARD, NEW YORK.

ENGINE-STOP DEVICE.

1,196,220.

Specification of Letters Patent. Patented Aug. 29, 1916.

Application filed September 8, 1915. Serial No. 49,472.

To all whom it may concern:

Be it known that I, GEORGE W. EDWARDS, a citizen of the United States, residing at Fort Edward, in the county of Washington 5 and State of New York, have invented certain new and useful Improvements in Engine-Stop Devices, of which the following is a specification, reference being had to the accompanying drawings.

10 This invention relates to an improved engine stop device and has for its primary object to provide a simple and positively operating means for automatically cutting off the supply of motive fluid to the engine 15 when the belt shifts to an excessive extent upon the fly wheel and there is imminent danger of the belt moving entirely off the wheel.

20 The invention has for a more particular object to provide a gravity controlled cable connected to the cut-off valve in the supply pipe, and means for holding the gravity means against operation, including a cable or other flexible member extending upon 25 each side of the fly wheel, contiguous to the edges of the belt and adapted to be engaged thereby to release the gravity means, whereby the same will act to cut off the supply of motive fluid.

30 The invention has for a further general object to provide a device for the above purpose which consists of very few parts of simple construction and arrangement so that the device is not liable to get out of 35 order but is reliable and efficient in practical use.

With the above and other objects in view, 40 my invention consists in the novel features of construction, combination and arrangement of parts to be hereinafter more fully described, claimed and illustrated in the accompanying drawing, in which,

45 Figure 1 is an elevation showing conventionally, an engine and its fly wheel with my improved automatic stop device applied thereto; and Fig. 2 is a top plan view.

50 Referring in detail to the drawing, E indicates an engine of any ordinary or approved construction, P the supply pipe for the engine, and V the controlling valve in said pipe.

W designates the fly wheel traversed by the belt B.

In the drawing, I have illustrated a centrifugally controlled actuating member 5 for the stop mechanism, which is mounted upon the fly wheel W. This device is fully illustrated and described in my Patent No. 1,137,054, issued April 27, 1915. The specific construction thereof will not, therefore, be set forth in the present application. In a suitable support 6, a vertically disposed lever 7 is fulcrumed intermediate of its ends, as indicated at 8. The lower end of this lever 7 is curved, as shown, and upon the same is hung a weight 9. An arm 10 is also fulcrumed intermediate of its ends in the support 6, as shown at 11, and one end of this arm is provided with an opening to receive the upper end of the lever 7 and hold the same against pivotal movement under the gravity action of the weight 9. The other end of this arm 10 is adapted for engagement by the centrifugally controlled actuating member 5 in the same manner as set forth in my prior patent hereinbefore referred to.

Adjacent to the engine proper, a second vertically disposed pivoted lever 12 and holding arm 13 are mounted, the lever 12 being provided upon its lower end with the weight 14. These parts are identical in construction and operation with the corresponding elements previously described. Upon a fixed arm 15, a guide pulley 16 is mounted, around which the cable or other flexible element 17 extends. One end of this cable is connected to the weight 9 while the other end thereof is connected to the pivoted arm 13. A wire or cable 18 is also connected to the weight 14 and extends upwardly over a guide pulley 19 and is attached to the arm a of an emergency valve A.

An operating cable 20 is trained around suitable guide pulleys 21 and has one of its ends extended upwardly and connected to the pivoted arm 10. This operating cable is so arranged as to provide parallel stretches disposed upon relatively opposite sides of the fly wheel W and contiguous to the edges of the belt B, the other end of the cable being suitably fixed to a stationary element, indicated at 22.

In the operation of the device as above set forth, it will be understood that, in the event of a lateral shifting movement of the belt B upon the periphery of the fly wheel, 5 to an excessive extent, the edge of the belt will engage one stretch of the operating cable 20, thereby causing said cable to exert a downward pull upon the end of the arm 10 and move the opposite end thereof upwardly to release the lever 7. The weight 9 will, therefore, act by gravity to pull upon the cable 17 and the second arm 13 will be actuated to release the lever 12 so that the weight 14 can act in a similar manner to 15 pull upon the cable 18 and operate the emergency valve A, whereby the supply of motive fluid to the engine cylinders will be cut off.

From the foregoing, it will be seen that I 20 have produced a simple and yet positively operating means which will act automatically upon the excessive shifting of the fly wheel belt to stop the operation of the engine. In view of the very simple arrangement 25 of the several coöperating elements, it is manifest that the invention may be applied to engines of the various types now in general use without necessitating any material alterations in their construction. 30 The device may also be produced at small manufacturing cost and provides a safe, reliable and convenient means for stopping an engine and obviating all possibility of injury thereto from accidental causes such as that above referred to.

While I have shown and described the preferred construction and arrangement of the several parts of the device, it is to be understood that the same is susceptible of 40 considerable modification therein and I, therefore, reserve the privilege of resorting to all such legitimate changes as may be fairly embodied within the spirit and scope of the invention as claimed.

45 Having thus fully described my invention, what I desire to claim and secure by Letters Patent is:—

1. The combination with an engine having an emergency valve controlling the supply of motive fluid thereto, and a fly wheel belt, of gravity actuated means for operating the said valve to close the same, and a movable cable having parallel stretches for engagement by the respective edges of the 50 fly wheel belt upon an excessive shifting movement thereof, whereby said gravity means is rendered operative to close said valve.

60 2. The combination with an engine having an emergency valve controlling the supply of motive fluid thereto, and a fly wheel belt, of gravity actuated means for operating the said valve to close the same, a latch element normally preventing the operation

of said gravity means, and a movable cable 65 connected to the latch element and extending adjacent to one edge of the fly wheel belt to be engaged thereby upon an excessive movement of the belt whereby the latch is operated to release the gravity means for 70 actuation and close the emergency valve.

3. The combination with an engine having a supply pipe and an emergency control valve therein, and a fly wheel belt, of a vertically disposed, pivotally mounted lever, 75 a gravity movable weight on one end of said lever, a cable connection between said weight and the emergency valve to operate the latter, a pivoted latch arm engaging said lever to normally hold the weight against gravity 80 movement, and an operating cable connected to the latch and disposed contiguous to one edge of the fly wheel belt to be engaged thereby upon an excessive movement of the belt, whereby the latch is operated and the 85 lever released to permit of the gravity movement of the weight whereby the emergency valve is closed.

4. The combination with an engine having a supply pipe and an emergency control 90 valve therein, and a fly wheel belt, of a pivotally mounted lever, a weight attached to said lever, a pivoted latch arm engaging the lever to hold the same against movement under the gravity action of the weight, operating means connecting the weight to the 95 emergency control valve, and an operating cable fixed at one of its ends and having parallel stretches disposed upon opposite sides of the fly wheel contiguous to the edges 100 of the fly wheel belt, the other end of the cable being connected to said latch arm, said cable being engaged by the belt upon an excessive shifting movement thereof to move the latch arm and release the lever, 105 whereby the control valve is closed in the gravity movement of said weight.

5. The combination with an engine including a fly wheel belt, said engine having a supply pipe and an emergency control 110 valve therein, of means normally holding said valve open during the operation of the engine and actuated by said fly wheel belt upon a slipping movement of the belt relative to the fly wheel, whereby the valve is 115 closed.

6. The combination with an engine including a fly wheel belt, said engine having a supply pipe and an emergency control valve therein, of mechanism operatively connected 120 to said valve to normally hold the same in open position during the operation of the engine, and means actuated by said fly wheel belt upon excessive lateral slippage thereof to permit said valve operating means to operate and close the valve.

7. The combination with an engine, controlling means therefor and a fly wheel belt,

of mechanism operatively connected to said controlling means including an element engaged and actuated by the belt upon excessive slipping movement thereof upon the fly wheel, whereby said mechanism is rendered operative to actuate the controlling means and stop the operation of the engine.

In testimony whereof I hereunto affix my signature in the presence of two witnesses.

GEO. W. EDWARDS.
